UNITED STATES PATENT OFFICE.

FRANCIS WILLIAM STOKES, OF MANSFIELD, ENGLAND.

CASTING-MACHINE.

1,302,448.

Specification of Letters Patent. Patented Apr. 29, 1919.

Application filed July 9, 1918. Serial No. 244,099.

To all whom it may concern:

Be it known that I, FRANCIS WILLIAM STOKES, a subject of the King of Great Britain, residing at 20 Alexandra avenue, Mansfield, Nottingham, England, have invented 5 new and useful Improvements in Casting-Machines, of which the following is a specification.

This invention relates to casting machines 10 of the kind in which a rotating mold is made use of, into which the metal or other material to be cast is introduced through a centrally arranged pourer from which it is projected against the inner periphery of the 15 rotating mold by the action of centrifugal force. My invention comprises certain improvements in apparatus of this class for the purpose of improving its efficiency and rendering it more adapted for use in specific 20 cases.

According to the invention the mold is made in two parts which are normally, that is to say, when the machine is at rest, automatically held in the separated or open 25 positions, but which, when the machine is rotated, are automatically closed by the centrifugal force generated by such rotation.

In the accompanying drawings:—

Figure 1 is a side view of one form of 30 centrifugal casting machine embodying the improvements.

Fig. 2 is an end view illustrating the mold and connections therefor.

Referring to the construction of casting 35 machine illustrated, which is designed for the production of small castings, *a* indicates the bed-plate of the machine, *b* indicates the two halves of the mold and *r* shows two bell-crank-levers, to one end of each of 40 which one half of the mold is secured. The said bell-crank-levers *r* are pivotally mounted at *r*¹ on the end of a spindle *s* which is mounted in bearings *s*¹, *s*¹ carried by the bed-plate *a* of the machine. The other ends of 45 the bell-crank-levers *r* are furnished with the weights *t* which are connected by the springs *u*, the elasticity of which draws the said weights *t* toward one another so as to open the mold when the machine is at rest.

50 When the mold is being rotated through the medium of the driving spindle *s*, the centrifugal force which is developed overcomes the tension of the springs *u* so that the weights *t* are caused to move apart and

thereby close the mold which is retained in 55 the closed position until the rotation of the said spindle ceases.

v is a plate which is freely mounted on the driving spindle *s* and is furnished with the cam slots *v*¹ with which engages pins *t*¹ 60 carried by the weights *t*, the object of this arrangement being to insure that the mold *q* is retained in the true axial position during rotation.

w indicates the pourer which is loosely 65 mounted in the support *x*, its outer end being furnished with a hand-wheel *y*, by means of which the said pourer can be turned and adjusted longitudinally as required in the operation of the machine. 70

Claims:

1. In a centrifugal casting machine of the kind herein referred to the combination with a multipart mold normally held separated or open, of means whereby the parts 75 of the mold are closed by centrifugal force generated by the rotation of the mold, substantially as described.

2. In a centrifugal casting machine as claimed in the preceding claiming clause, 80 the construction wherein the mold is made in two parts each carried upon a pivoted lever mounted upon a driving spindle and means for retaining the said levers in a position such that the mold is open when at rest, 85 and closed when under the action of centrifugal force generated when the mold is rotated, substantially as hereinbefore described.

3. In a centrifugal casting machine of the 90 kind claimed in the preceding claiming clause, the construction wherein each of the half-molds is carried on one arm of a bell-crank lever pivoted to a driving spindle and the other arm of which carries a weight, the 95 two weights being connected together by a spring device, substantially as described.

4. In a centrifugal casting machine as claimed in the preceding claiming clause the provision of means such as a slotted plate 100 with which pins upon the weights engage for maintaining the mold in the true axial position during rotation, substantially as described.

FRANCIS WILLIAM STOKES.
